U.S. Cl. D96—12

FIG. 1

FIG. 2

FIG. 6

FIG. 3

FIG. 4

FIG. 5

FIG. 1 is a perspective view taken from the front and right side of a price indicator sign showing my new design.

FIG. 2 is a top plan view thereof.

FIG. 3 is a rear elevational view thereof.

FIG. 4 is a right side elevational view thereof, the left side being a substantially identical mirror image.

FIG. 5 is a bottom plan view thereof.

FIG. 6 is an enlarged, fragmentary, cross-sectional view taken in the direction of line 6—6 of FIG. 1.

The broken line representation of indicia in FIG. 1 is for purposes of illustration only.

The characteristic feature of my design resides in the raised vertical flanges on each side of the front panel in association with the horizontal line of price indicator

openings located in said front panel midway between the top and bottom of said flanges.

I claim:

The ornamental design for a price indicator sign, as shown and described.
